CHECKERWORK

Application filed January 18, 1928. Serial No. 247,570.

This invention relates to a new and improved design of checkerwork for hot blast stoves, and more particularly to such a design adapted to substantially increase the heating efficiency or transfer of heat in the checkers and to increase the heating surface of a given stove.

Hot blast stoves for heating the air for blast furnaces have been constructed with checkerwork of various design. The usual checker employed in this country is built up out of brick placed on edge in such a way as to form square openings. In former years hexagonal brick with round holes were frequently used. Other special shapes have been employed in the past, generally with a view of stiffening the checker column and preventing shifting of the checkers through pressure from the expanding combustion chamber wall, but in every case the checker openings were of the same size from top to bottom and the heating surface was the same in every cross section of the checkerwork throughout the height of the stove, which is usually from eighty to one hundred and ten feet.

This uniform construction has the disadvantage that the top checkers do most of the work of heat exchange, both during the period of heating and of giving off heat to the blast. The top checkers are heated to very nearly the same temperature as the combustion chamber, that is, to a bright red heat, and the checkers about thirty feet down are heated to a dull red heat. Below this point the checkers remain black and the lower half of the checker column does but very little work. In other words, the temperature at the top of the checkers is usually around 2000° F., thirty feet down approximately 1200° and fifty feet down about 800°, or very close to the usual chimney temperature of 600°.

There are two reasons for the inefficient work performed by the lower portion of the checkerwork. One reason is that the heat exchange is more rapid and more penetrating the higher the difference in temperature of the heat exchanging mediums. In other words, the heat transfer is a function of the

heat head, but it is also a function of the velocity of the gases. When the stove checkers are of equal design all the way through the checker column, the combined open area through the checkers being the same from top to bottom, the velocity of the hot gases is very much greater at the top of the checkers than at the bottom, also the velocity of the cold blast is very much greater at the top of the checkers than at the bottom. If the temperature at the top of the checkers is 2000° and at the bottom 500°, the ratio of velocities is approximately two and one-half to one. In the case of the cold blast, the difference is even greater, being more nearly three to one when high blast temperatures are carried.

We have invented a type of checkerwork which permits of a decrease in the size of the checker openings in the bottom part of the stove as compared to the top part of the stove, with the result that the velocities are equalized to whatever extent desired. Since it would require too many different sizes of brick to reduce the sizes of the flues continually from the top down, layer for layer, we preferably make the gradation in three or four steps only. Our checkerbrick is octagonal in shape, the brick having eight sides of which four are much longer than the other four. The octagonal brick have round holes in the center. The four longer sides form the walls of the square checker openings between the octagonal brick, as shown on the drawing. For manufacturing reasons these brick may be split vertically through the center openings and made as two separate brick. All these brick may, however, be readily manufactured as a continuous ribbon of clay forced from the dies of a usual brick or tile machine.

We are aware that octagonal brick have been used before in such a way as to leave square openings between them, but such brick had substantially equal sides. The advantage of making the sides which form the square openings longer is that the brick areas between each two round openings are reduced. It will be noticed that with the octagonal design of checker brick the center

portion of the brickwork between two round openings is furthest removed from the walls of the checker flues and therefore the least accessible to the flow of heat and the least useful for heat transfer. By lengthening the walls of the square openings, this area is substantially reduced, therefore the checkerwork becomes relatively more efficient as compared to checkerwork built up with octagonal brick having substantially equal sides, such as have been heretofore used.

In order to reduce the cross-sectional area of the checker openings from the top to the bottom, we may employ brick with thinner walls in the top section of the checker column and brick with heavier walls in the bottom section, grading this construction as stated before by having preferably three or four sections in the checker column, the bottom section of the column having walls $2\frac{1}{2}$ inches thick, the center section walls 2 inches thick and the top section walls $1\frac{1}{2}$ inches thick, resulting in the openings in the top section being $5\frac{1}{4}$ inches and the center section $4\frac{1}{4}$ inches and the bottom section $3\frac{1}{4}$ inches in diameter. The long sides of the octagonal brick may be curved or angular with the result that the square openings will have curved or angular walls. This results in a decrease in the area of the square openings. These designs have the further advantage of strengthening the checker column in the bottom sections, the heavier wall thickness rendering the structure more massive and more rigid and also easier to support on the arches below due to the heavier walls at the point of contact with the arches.

Another method of increasing the velocities in the bottom section of the stove as compared to the top sections, is to insert fillers in the lower sections to produce the desired gradation. We insert loose brick as fillers in the square and round openings in the bottom section. The corners of these loose brick are preferably chamfered or rounded. The chamfer of the filler brick for the square is at an angle of 45° , and the corresponding portions of the filler brick for the round openings is curved so as to conform to the contour of the round holes in the octagonal brick. The advantage of shaping the filler brick in this manner is that they will make a better fit and therefore form a more stable structure. It is desirable to have the same storage of heat in the fillers as well as in the walls of the checkers per unit of surface. For instance, if the wall thickness of the checkers is two inches, that of the filler should be two inches also in order to transfer the heat in the same unit of time. The sides of these brick may be rounded, triangular or corrugated in form. The two sides of the bricks may be formed differently and superposed brick turned end for end so as to expose different forms of sides in the passageways. The flow will be broken

up and large surfaces brought in contact with the gases.

These filler brick should be staggered in successive vertical sections of the structure. This has the advantage of forcing the gases as well as the hot air to zigzag through the checkers and to impinge against the lower surfaces in the case of the gas, and in the upper surfaces in the case of the air of the filler brick. The zigzag course and the impingement will cause turbulence of the gas and air, the swirls and eddies compelling positive impingement against the side walls and greatly increasing the heat transfer in accordance with well established laws. In the center section we may put the insert in the square openings only and may place no fillers at all in the top section of the checkerwork.

Another form of construction consists in using loose bricks of different thickness in the passages in the various vertical sections of the checkerwork. The bricks in the lower section would be thickest, with thinner bricks in intermediate sections and preferably none in the upper section. In any form of construction it is desirable to have the passages clear in the upper portion as in such portion the passages tend to partially choke with loose material carried by the gases, and also at this point of greatest heat there is a tendency for the checker brick and solids to flux and flow to some extent, thus reducing the effective passage area for gases and air.

The bricks in the bottom tier are preferably supported by metal bars which are made from heat resisting steel. These bars preferably rest immediately on top of the arches or cross walls and extend clear across the checker area from combustion chamber wall to side wall. In order to decrease the movement caused by expansion and contraction, these bars are preferably made in one or more sections with interlacing joints. This method of support is new and can be employed as well for the fillers as for the checkerwork. If metal bars are employed for supporting the fillers only, they may be rested on a bottom layer of checkers, these then having no fillers.

It is an object of the present invention to provide a new and improved design of checker brick and checkerwork construction.

It is a further object to provide a brick and construction adapted to substantially increase the heating efficiency or transfer of heat over that of present checkers of usual construction.

It is an additional object to provide a checker brick and construction which will increase the heating surface of a given stove.

It is also an object to provide a checker brick and construction of this character which will be simple in design and construction,

and adapted for commercial manufacture and installation.

Other and further objects will appear as the description proceeds.

5 We have illustrated certain preferred embodiments of our invention in the accompanying drawings, in which

Figure 1 is a fragmentary horizontal section of one form of construction;

10 Figure 2 is a similar view of a modified form of construction;

Figure 3 is a perspective view of one of the bricks;

15 Figure 4 is a view similar to Figure 1 showing a further modification;

Figure 5 is a view similar to Figure 1 showing a still further modification;

20 Figure 6 is a fragmentary plan view on a reduced scale showing the method of supporting the brick;

Figure 7 is a fragmentary section taken on line 7—7 of Figure 6;

25 Figure 8 is a fragmentary vertical section, showing the special form of meeting surfaces of certain brick;

Figures 9 to 13 are fragmentary horizontal sections showing further forms of loose brick construction; and

30 Figure 14 is a vertical section through the form of construction shown in Figure 2.

Referring first to Figure 3, the preferred form of brick is octagonal in form having a central opening 11 which is circular in cross section and passes through the brick from end 35 to end. The four shorter sides 12 of the brick are placed alternately between the longer sides 13. It will be noted that the sides 13 exceed in width the sides 12 by more than one-third of the width of the latter sides. Also 40 any two opposite sides 12 are further apart measured diametrically across the brick than any two opposite sides 13.

The brick shown in Figure 3 is provided upon its lower face with notches 14 adapted 45 for the passage of the bar 15, the use of which will be explained in detail hereinafter. It will be understood that only a portion of the bricks will be formed with the notches 14, the majority of them being without these notches 50 and identical upon either end.

In making up the brickwork a plurality of the brick 16 of Figure 3 are placed together with their narrower sides 12 in contact, as 55 clearly shown in Figures 1 and 2. This form of building up the brick causes their longer sides 13 to be spaced apart to form the vertically extending passageways 17. The size of the central passageway 11 in some of the bricks used in the lower courses of the structure 60 may be reduced as shown by the circular lines 18 appearing in Figure 1, and the passages 17 may be similarly reduced as shown at 17'.

In the form of construction shown in Figure 2, the special loose brick 19 are placed in

the passageway 17, these bricks having their portions 20 formed to conform substantially to the contour of the corners of the passageways in which they are diagonally placed.

The filler brick are so designed and sized as 70 to fit sufficiently loosely to allow for ordinary variation in size in manufacture.

The filler brick may preferably be so proportioned as to have a thickness substantially equal to the thickness of the walls surrounding the 75 passageways. The brick 19 may be placed in

either diagonal direction, as shown in Figure 2, and in the preferred form of construction a number of successive bricks will be placed 80

extending in one direction in the column and then a series of superposed brick will be placed extending in the opposite direction in

angular relation to the first series. These 85 bricks serve to divide the passageways 17 and to decrease the effective passage area of such

passageways. It will be noted that the thickness of the brick 19 may be substantially that

existing between the walls 13 and the central 90 passageway 11 of the brick 16. Thus both

the loose brick and the brick making up the body of the checkerwork will serve with equal

facility for taking up heat from the blast 95 gases and discharging this heat to the incoming hot blast. The brick 21 are similarly located in passageways 11 formed in the brick

16. These brick 21 may have their side edges 22 arcuate in form to substantially conform 100 to the contour of the circular passage in which they are placed. It will be understood that

in the complete construction of a hot blast stove by the use of the form of construction

shown in Figure 2, the brick 19 and 21 will 105 preferably be placed in all passages in the lower portion of the stove. The effective pas-

age area for the gases will thus be reduced at this point where the volume of the hot blast

gases has been reduced to the greatest extent

by having given up their heat to the checker- 110 work. Similarly, these flues of least area will receive the comparatively cold incoming

hot blast air when its volume is least before

it has been expanded by the heat picked up 115 from the checkerwork. In the intermediate vertical sections of a stove the brick may be placed in only one set of passageways, that is

either the passageways 11 or 17. Preferably where this form of construction is used, they

will be left out of the passageways 11 and placed only in the passageway 17. At this

point in the stove, the heat gases will have 120 been partially reduced in volume and the hot

blast air will have been partially expanded in

volume and the additional space provided by

the removal of part of the brick will provide

such an area as to maintain the velocity of

flow of both gas and hot blast air approxi- 125 mately uniform. In the topmost portion of

the stove no bricks will be placed in either

set of passages. Here both the blast gases

and the hot blast air are at their greatest tem- 130

perature and require the greatest passage area if their velocity is to be maintained.

In the form of construction shown in Figure 2, the loose brick are shown as of greater size in the lower section of the checkerwork than in an intermediate portion. By this means brick will be located in all vertical passageways both in the bottom and intermediate sections. The variation in the thickness of the loose brick will take care, however, of the desired greater reduction in area of the passageways in the lower section and lesser reduction of area in the intermediate section. It will be understood that, if desired, brick of more than two sizes may be used, so that there may be more than two sections with brick of less thickness in the sections as the sections approach the top section, which section will preferably have its passageways without loose brick.

The forms of construction shown in Figure 1 will take care of the desired reduction in area to same extent by using brick having interior passageways 11, gradually decreasing 25 in size as the brick approach the bottom of the stove. It will be understood that the passageway 11 will not be tapered in individual brick nor will there be a continuous small variation, but normally brick having different sizes of passages will be used in the various vertical sections of the stove. Similarly, the area of passageways 17 will be reduced, as shown in the figure.

In the form of construction shown in Figure 4, the brick 24 are provided with narrow contacting sides 25 similar to the sides 12 of the brick 16 of Figure 3. The sides 26 of the brick project into the passageways 27 and reduce the effective area of these passageways 40 while increasing the surface area of the passageways contacting with the gases flowing through them. The central passageways 28 in the brick 24 have their surfaces corrugated, as shown at 29, in order that the area 45 of contact with the gases may be increased.

In Figure 5 there is shown a form of construction quite similar to Figure 4, with the exception that the sides 30 of the brick 31 are more rounded than the similar sides 26 of the brick 24. The passages 32 are thus greater in area than the passages 27. The passages 33 extending through the brick 31, have their surfaces corrugated, as shown at 34. These corrugations 34 are flatter than the corrugations 29 and the area of the passageways 33 is greater than the area of the passageways 28.

It will be understood that these typical forms shown in Figures 4 and 5 may be used 60 alone or combined with the forms shown in Figure 2. For example, the form shown in Figure 4 having the least passage area, may be used for the lower portion of a stove, the form of construction shown in Figure 5 may 65 be used for an intermediate portion of a stove,

and the form of construction shown in Figure 2 may be used for the upper portion of a stove. In this case it will be understood that there will be no loose brick in the passageways of the stove.

In Figure 8 is shown the form of the meeting surfaces of superposed brick which are turned at right angles to each other. In order to avoid the great restriction in area available for flow at this point if the brick 70 were of usual type, the meeting faces of the brick are cut away as shown at 45. The brick thus permit free passage of gases as they are cut away except upon the central portion where the brick contact. It will be understood that only one form of special brick will be necessary for this purpose as the two meeting brick are identical in form, one being merely inverted relative to the other.

In the form of construction shown in Figure 9, the loose brick 46 are provided with concave portions 47 and convex portions 48 which increase the contact area for heat transfer and also form passage spaces without narrow corners which would be to some 80 extent dead air spaces. In Figure 10 the brick 49 is generally similar to that of Figure 9 but one side 50 is corrugated which increases the contact area and also assists in causing swirls which will increase the contact and heat transfer. Alternate bricks or occasional bricks may be turned end for end so that some sides will be smooth and others corrugated in the same line.

In Figure 11 we have shown a form of loose 90 brick 51 in the passageways 11 having angular sides 52. Lower brick 53 are shown having angular sides projecting further into the passageways. Similar brick 54 are placed in passageways 17 and brick of greater thickness 55 are shown below the brick 54. While brick of only two thicknesses have been shown in this figure, it will be understood that a large number of different thicknesses of brick of the same general contour may be used if 100 desired. The brick 55 of Figure 12 have the convex portions 56 but have no concave portions as shown in Figure 9. In Figure 13 the brick 19 in the passageways 17 are similar to those of Figure 2 and the brick 22 in passageways 11 are also similar to Figure 2. Instead, however, of a number of brick being placed in one direction and then others at right angles, in this form of construction the brick 22 are turned slightly relative to each other 115 forming a gradually twisting passage for gas flow. It will be understood that these forms are illustrative and that many other forms of brick may be used.

The loose brick shown in the drawings 125 are preferably supported in the passageways by means of the iron or steel rods or bars 15, shown in section in Figure 3, and also indicated in Figure 2. These bars may be placed through special blocks provided with notches 130

14 in the lower portion of the stove. In the preferred form of construction, there will be no loose brick in the lowermost course of brick 16 and the bars 15 will rest on top of the lowermost course fitting in notches 14 in the bottom of the next course of brick. Additional sets of rods 15 may be placed at vertically spaced points in the structure so that the loose brick will not all be directly supported from the bottom.

In order to increase the stability of the structure part size brick 16 will be provided, that is, brick of part the height. By the use of such brick in the lower portion of the structure, the brickwork may be built up so that the horizontally extending joints between superposed brick will be located in different planes in adjacent brick columns. By means of this breaking of joints the structure will be rendered more stable, as it will be impossible for any one horizontal tier of brick to move relative to the tiers above or below. The breaking of horizontal joints also facilitates the erection of the structure.

The method of supporting the lowermost brick has been indicated in Figures 6 and 7. The central portion of the stove is shown at 36 and the outer shell at 37. The supporting arches 38 extend radially outward from the central portion to the brick lining 39 of the shell. These arches 38 support a plurality of metal supporting beams 40. These beams 40 are made up of a plurality of sections having lapped joints 41. In so far as possible the sections and lapped joints are made of such length that the lapped ends of the adjacent bar rest upon a brick supporting arch 38. As shown in the lower portion of Figure 6, the brick 16 rest directly on the metal portions 40. These beams are of such size and so spaced as to be substantially clear of all of the vertically extending openings 11 and 17. It will be noted that as shown in the figure, the special brick 16 will preferably not be broken to fill up the stove but bricks 42 of usual rectangular shape will be used to fill up irregular portions of the brick structure.

While we have described several preferred designs of brick and constructions for carrying out our purpose of equalizing the velocities of flow of heat exchanging gases through the checkerwork, there are many further designs of brick and of checker construction which are capable of carrying out our objects and we contemplate such further changes and modifications as come within the spirit and scope of the appended claims.

Our constructions also serve to increase the total effective heating surface as well as to equalize velocities of flow and in addition provide structures of greater strength and stability than usual types of construction. The brick and methods of construction are

simple in design and are capable of commercial manufacture and installation.

We claim:

1. A checkerwork construction comprising a plurality of brick laid in superposed tiers continuous vertically extending passageways through said brickwork, and separate means inserted in said passageways whereby the effective area of said passageways for the passage of gases is successively reduced.

2. A checkerwork construction comprising a plurality of brick laid in superposed tiers, continuous vertically extending passageways through said brickwork, and separate means whereby the effective area of said passageways for the passage of gases is greatest in the upper tiers of said construction, less in intermediate tiers and least in the lowermost tiers.

3. A checkerwork construction comprising a plurality of brick laid in superposed tiers, vertically extending passageways extending through said checkerwork, and a column of brick loosely placed in certain of said passageways to divide the passageways, said brick fitting sufficiently loosely to allow for ordinary variation in size in manufacture.

4. A checkerwork construction comprising a plurality of brick laid in superposed tiers, vertically extending passageways extending through said checkerwork, and a column of brick loosely placed in certain of said passageways to divide the passageways, said brick fitting sufficiently loosely to allow for ordinary variation in size in manufacture and certain of said loosely placed brick being placed in angular relation to other of said brick.

5. A checkerwork construction comprising a plurality of brick laid in superposed tiers, vertically extending passageways extending through said checkerwork, and brick loosely placed in certain of said passageways to divide the passageways, said brick fitting sufficiently loosely to allow for ordinary variation in size in manufacture, said loosely placed brick being in more of said passageways in the lower portion of the structure than in a superposed portion.

6. A checkerwork construction comprising a plurality of brick laid in superposed tiers, vertically extending passageways extending through said checkerwork, and brick loosely placed in certain of said passageways to divide the passageways, said brick fitting sufficiently loosely to allow for ordinary variation in size in manufacture, said loosely placed brick being of greater thickness in said passageways in the lower portion of the structure than in a superposed portion.

7. A checkerwork construction comprising a plurality of brick of generally similar contour, said individual brick having vertically extending passageways extending therethrough, said brick being laid in superposed

tiers with additional passageways formed therebetween, and loosely placed brick located in the tiers of brick in both sets of passageways, said brick fitting sufficiently loosely to permit their ready insertion with normal variation in size of manufacture, said brick being of greater thickness in the lower tiers than in intermediate tiers and no brick being placed in the passageways in the uppermost sets of tiers.

8. A checkerwork construction comprising a plurality of brick of generally similar contour, said individual brick having vertically extending passageways extending therethrough, said brick being laid in superposed tiers with additional passageways formed therebetween, and loosely placed brick located in the tiers of brick in both said sets of passageways, said brick fitting sufficiently loosely to permit their ready insertion with normal variation in size of manufacture, loosely placed brick being of less thickness in the passageways in vertically intermediate sets of tiers than in the lower tiers, and no brick in the passageways in the uppermost sets of tiers, certain of the brick in each passageway being placed in angular relation to other brick in the same passageway.

9. A checkerwork construction comprising a plurality of brick, said construction having therein a plurality of vertically extending passageways, additional special brick placed in columns in said passageways, said brick extending diagonally of the passageways and dividing said passageways, and certain of said brick being placed in angular relation to other of said brick.

10. A checkerwork construction comprising a plurality of brick, said construction having therein a plurality of vertically extending passageways, additional special brick placed in columns in said passageways, said brick being formed with vertically extending faces adapted to substantially conform to the contacting portions of the passage walls.

11. A checkerwork construction comprising a plurality of brick placed in superposed courses, a support construction below said brickwork, and a plurality of metal members supporting the brickwork from said support construction, said metal members being short in length and adjacent members in the same line having overlapped ends, said overlapped ends being located above elements of the support construction.

12. In a checkerwork construction, a plurality of brick laid in superposed tiers, vertically extending passageways through said brickwork, brick placed in certain of said passageways and metallic members carried by the first named brick and extending across said passageways to support the last named brick.

13. In a checkerwork construction, a plu-

rality of brick laid in superposed tiers to form vertically extending passageways, metal members supported by certain of said brick extending across the passageways and within the contour of the brick, and additional brick placed in said passageways and supported on said members.

14. In a checkerwork construction, a plurality of brick having vertically extending passageways formed within the brick, said brick being built up in superposed tiers to form additional passageways between the brick, metal members supported by certain of said brick extending across certain of the passageways, and additional brick placed within certain of said passageways and supported on said members.

15. In a checkerwork construction, a plurality of brick having vertically extending passageways formed within the brick, said brick being built up in superposed tiers to form additional passageways between the brick, metal members supported by certain of said brick extending across passageways both in said brick and between said brick, and additional brick placed within said passageways both in said brick and between said brick and supported on said members.

16. Checker bricks adapted to engage other bricks in angular relation, said brick having reduced engaging faces and having portions of the adjacent faces cut away upon an angle to facilitate passage of gases at the plane of the engaging faces.

17. In a checkerwork construction, a plurality of brick forming vertical passageways, other brick located in said passageways, certain of said other brick being in angular relation to each other, said brick having reduced engaging faces and the adjacent surfaces of said angularly related brick being cut away to facilitate flow of gases through said passageways at and adjacent the plane of the meeting faces.

18. A checkerwork construction comprising a plurality of brick placed in superposed courses, a support construction below said brickwork, and a plurality of metal members supporting the brickwork from said support construction, said metal members being short in length and adjacent members in the same line having overlapped ends.

19. In a checkerwork construction, a supporting structure, a plurality of brick laid in superposed tiers, vertically extending passageways through said brickwork, bricks placed in certain of said passageways and metallic members extending within the contour of the passageways in the brickwork and supporting the brick placed in said passageways.

20. A checkerwork construction comprising a plurality of brick placed in superposed courses, a support construction below said brickwork, and a plurality of metal mem-

bers supporting the brickwork from said support construction, said metal members being short in length and placed in aligned relation in substantially parallel lines.

5 Signed at Chicago, Illinois, this 16th day of January, 1928.
